SLIPPER

Filed May 28, 1928

WILLIAM HUBBARD Inventor

By Martin & Rendell

Attorneys:

UNITED STATES PATENT OFFICE

WILLIAM HUBBARD, OF DOLGEVILLE, NEW YORK

SLIPPER

Application filed May 28, 1928. Serial No. 281,163.

My present invention relates to completely formed and finished heels adapted to be applied bodily to soft-soled slippers and to the process of forming such heels and of making 5 slippers by using such heels, and to soft-soled slippers having a rigid or solid heel.

One purpose of this invention is to provide as a new article of manufacture a completely formed and finished heel adapted to 10 be applied bodily to soft-soled slippers or slippers for indoor wear by nailing the said pre-finished heels to the slipper by nails passing from the inside of the slipper down into the pre-formed heel and further to provide 15 features of constructing such heels that will render it well adapted for the use intended and allow the heel to be securely fastened in place and at the same time have the heel neat in appearance and durable in use.

20 A further purpose is to provide a pre-formed heel especially constructed and shaped to fit the heel of a soft-soled slipper and to hold the heel portion of the slipper permanently in proper position and to reinforce and strengthen the counter of the 25 slipper if one be used.

Further purposes of this invention are to point out processes for the economical and efficient making of such a completely formed 30 heel and to show the process of applying such a heel to a soft-soled slipper and further to provide as a new article of manufacture a soft-soled slipper having a solid or rigid heel.

35 In the manufacture of hard-soled shoes and slippers the hard sole extends through for its full thickness or even at increased thickness to the rear of the heel and provides the base or foundation layer for the heel of sufficient 40 thickness and stiffness to have built thereupon the successive intermediate layers of heel blanks of leather or substitutes therefor by nailing said layers to the heel portion of the hard sole by nails pointed into and 45 through the sole from outside the slipper. To this partly formed heel the lower lift of leather is secured by nails passing upward into the other layers of the heel. The projecting edges of the heel portion of the sole 50 and of the heel blanks and in some cases the

edge of the lower lift are all together trimmed down to the proper size and shape for the completed heel.

Heretofore there has not been produced a soft-soled slipper having a rigid heel for the reason that the absence of a stiff rigid heel portion on the sole has prevented the making of stiff or rigid heels. It has been long recognized that soft-soled slippers are comfortable for the front of the foot but are uncomfortable for the back of the foot in that even in a rest slipper the heel of the foot needs a stiff heel of appreciable height. I have overcome the above mentioned disadvantages of soft-soled slippers by forming a slipper which is soft-soled but has a rigid heel of appreciable height and one which furthermore is strong enough and properly shaped to support a counter which is necessary to give further comfort and reinforcement to the heel of the foot even in a soft-soled slipper.

Fig. 1 is a side view of a soft soled slipper having a counter and embodying my invention.

Fig. 2 is a similar view of a slipper without a counter but embodying this invention.

Fig. 3 is a perspective view on a larger scale of a completely formed and finished slipper heel embodying my invention.

Fig. 4 is a vertical sectional view on line 4—4 of Fig. 3 and Fig. 5 is a similar longitudinal sectional view on line 5—5 of Fig. 3.

Fig. 6 is a cross sectional view similar to Fig. 4 after the leather cup lift 12, the two or more layers of leather board 13 and 14 and the leather top lift 15 have been fastened together by the upper and lower metal slugs 16 and 17 respectively but before the heel has been compressed into its ultimate form and before its edges have been trimmed or its edges and surfaces finished.

Fig. 7 is a vertical sectional view on line 7—7 of the slipper shown in Fig. 1.

Fig. 8 is a vertical cross sectional view through a compression mechanism adapted to compress a heel with a heel therein in the shape the parts have before the compression step takes place.

Fig. 9 is a vertical cross sectional view on line 9—9 of Fig. 2.

Referring to the drawings in a more particular description Figs. 1 and 2 show indoor slippers having soft soles 18 sewed about the sides and toe to the upper 19 of the common construction of soft soled or indoor slippers. Each of these slippers is provided with a relatively stiff shank 20 extending rearwardly through the instep portion of the slipper substantially to the rear end of the heel portion of the slipper but with the soft sole terminating slightly back of the front edge 21 of the pre-formed heel 22.

The form of slipper shown in Fig. 1 is provided with a counter 23 and an outside quarter 24 and an inside quarter 25. In the form of slipper shown in Fig. 2 my pre-formed heel is combined with a soft soled slipper having no counter and no inside or outside quarter.

The pre-formed or completely formed and finished heel 22 shown separately in Fig. 3 includes a cup lift 12, two or more layers of leather boards 13 and 14 and a leather top lift 15. The original shape, size and arrangement of these parts when first assembled is clearly shown in the transverse vertical sectional view thereof Fig. 6. It will be seen that the cup lift 12 and the top lift 15 and the lower lift or lifts 14 of leather boards or the like are all flat, that is having substantially parallel faces. The one or more upper layers 13 of leather board, however, are as shown in Fig. 6 plano-concave, that is level towards the cup lift and concave at the surface towards the lower layers 14 of leather board, leaving a lens-like space 26 between said two sections 13 and 14 of leather board, with the two sections of leather board in contact with each other about the horse shoe shaped outline of the heel; that is at the opposite sides 27 and 28 and the back side, but with said two sections of leather board spaced apart along the breast or front edge 21 about as shown in the sectional view, Fig. 6. With the cup lift 12 the intermediate lifts 13 and 14 and the leather top lift 15 in this position the said four parts are fastened or nailed together by the upper and lower metal slugs 16 and 17 respectively placed at intervals about the said horse shoe shaped part of the heel where the intermediate layers 13 and 14 are in contact or nearly in contact. It will be seen that the upper slugs 16 come down through the cup lift 12, the thick part of the lift 13 into and preferably through the lift 14 and somewhat into the top lift 15. The lower slugs on the other hand are driven first into the leather top lift and pass through the intermediate layer 14 and into the thick part of the other intermediate layer 13.

The heel so far assembled and with its parts fastened together is then placed inside of a ring 40' and properly shaped upper 65 and lower dies or shaping members 40 and

41 as shown in Fig. 8 are forced together with great pressure so that the intermediate layer 13 is compressed closely down against the opposing level surface of the other intermediate lift 14, leaving a concave surface on this lift 13 on its face toward the cup lift and the cup lift is bodily curved down with the parts assuming the position shown in Figs. 4 and 5. It will be understood that after this compression step the parts will remain permanently in the position indicated in Figs. 4, 5 and 3 and particularly that there will be a heel seat 30 about the said curved or horse-shoe shaped outline of the heel following the lateral sides 27 and 28 and the rear side 29 and that this heel seat will consist of a substantially level narrow surface 31 adjacent the said outer edges of the heel with an inward sloping part 32 first sloping down sharply and then more gradually towards the flat or slightly concave main central portion 33 of this whole face of the heel. Preferably about the forward third of this face of the heel is depressed slightly below the remaining part as indicated by the slight shoulder 35 in Figs. 3 and 5.

The heel so permanently compressed and with its parts securely fastened together by the said metal slugs is then successively put through the different finishing steps which in detail will ordinarily be as follows: First, the heels will be sanded with coarse paper which step takes the place of the trimming done upon a heel built up upon a shoe. Then the heel is sanded with medium grit and then with fine grit; then the heel is inked as black or brown and then burnished on all sides and usually the level surface 31 of the heel seat is treated with a beaded wheel and the outer edge of the heel if desired is ornamented by a wheel. The heel is now all formed, shaped and completely finished and ready to be attached to a soft-soled slipper as a finished heel by nailing from the inside of the slipper. It will be understood that such completely formed and finished heels are really separate units and may and ordinarily will be made in one factory and sold as separate articles to be affixed to a soft-soled slipper in another factory.

The construction of a soft-soled slipper by the use of the said pre-formed and neatly finished heel 22 will now be described, and first in connection with a slipper such as shown in Fig. 1 having a counter 23 with the outside quarter 24 and inside quarter 25. The forward part of this slipper will be made in the usual way of a soft-soled slipper by sewing the upper 19 to the soft sole 18 as far back as the soft sole extends, namely to a point a little to the rear of the front face 21 of the heel. The slipper is provided with a shank 20 of stiff material which preferably extends substantially to the rear end of the slipper. The lower edge of the counter 23

and likewise of the outside quarter 24 are turned in below the shank viewing the slipper as ultimately used but above the shank as the slipper at this stage is turned over in the hands of the workmen with the sole facing upward. The said inturned parts of the counter and outer quarter are tacked to the shank 20 by lasting tacks 36 which ordinarily will extend up into the layer of fiber called fiber tuck 37 usually placed below the inner or sock lining 38. The inturned edge of the inside quarter 25 will usually be placed between the shank and the said fiber tuck. At the central portion of the heel there will be the necessary amount of hair felt filler 39 to round out or level the bottom of the heel portion of the slipper between the inturned edges of the counter and outer quarter.

The slipper made substantially as described except that the sock lining 38 is not yet in place, is now ready to have fastened thereto the pre-formed heel 22. This is done by fitting the heel portion of the slipper into the concave face with the heel seat accurately fitting the slipper below the bend of the counter and fastening the slipper to the heel by nails or screw-like nails 42 passing downwardly through the fiber tuck 37 if that be used and through the shank 20 and well down into the finished heel but not therethrough. The sock lining 38 is then placed in the slipper covering the heads of the main nails 42 and the slipper is then completely finished.

It will be noted particularly that the pre-formed and completely finished heel 22 is rigid and of sufficient height to make the slipper comfortable. It will be seen also that the slightly cup-shaped upper surface of the heel together with the sharply raised heel seat around its outer edges is rigidly shaped to hold the portion of the slipper thereabove in the desired slightly curved or recessed form which will render the slipper comfortable and maintain the inner surface of the slipper permanently in that form. The curved face 32 of the heel seat supports the counter at the bend of the counter and so helps to hold the counter inwardly against the heel of the foot in snugly engaging position as has been done heretofore only with hard-soled shoes.

The relatively stiff shank 20 extending from just forward of the instep to the rearward portion of the pre-formed heel forms the main basis for the rigid securing of the heel to the slipper and also bridges over the instep portion of the slipper from the front of the heel so as to support the instep and make the slipper more comfortable.

It will now be seen that I have provided a new form of soft-soled slipper by providing a slipper having a soft-sole at the front and extending through but terminating substantially at the breast of the heel and so making the slipper comfortable for the front of the

foot, but have provided the heel portion of the slipper with a construction very similar to that used in an ordinary shoe in that in the full form of the invention the heel of the foot is supported by a counter and a rigid heel. The soft sole of the slipper, however, is not interposed between the rigid heel and the counter and its adjacent inner and outer quarters as such soft sole interposed between these two parts would make a spring heel or an elastic heel. I therefore terminate the soft sole substantially at the breast of the heel by bringing just the extremity of the soft sole between the pre-formed heel and the counter and shank enough to hold the soft sole in place but not enough to interfere with the rigidity and solidness of having the rigid heel fastened directly to the rear body of the slipper consisting of the shank or in the full construction of my invention the shank, the counter and the inner and outer quarters. The instep portion of the slipper, that is from the ball of the foot to the heel, is a compromise as it were between a hard-soled slipper and a soft-soled slipper in that the soft sole extends from the front of the foot to the heel but is supported and made comfortably rigid from the ball of the foot to the breast of the heel by the shank extending from the ball of the foot to and beyond the breast of the heel. By combining with the features of a soft-soled slipper terminating at the breast of the heel but provided with a counter of stiff material extending to the rear of the heel and forming on this counter a rigid heel and preferably a rigid heel having an upward extending ridge about its sides and rear to support the counter I have produced a slipper construction which has a firmness about the heel that is necessary for comfort but which has not been accomplished in a soft-soled slipper before and I have avoided the softness or springing action at and about the heel heretofore common with soft-soled slippers.

The rigid heel of my slipper has to be pre-formed because there is no rear part of a hard sole on the slipper to start the building up of an ordinary hard heel. The rear part of the shank is the rigid part of the slipper that is made the basis of my rigid heel construction but it is not practical to build a heel piece by piece thereon and then finish that heel by trimming it around the sides, rear and breast as is done in the ordinary shoe construction because such built-up heel would have to be trimmed right to the adjacent surface of the soft leather outer quarter and the breast of the heel to the soft leather of the soft sole which cannot be done without cutting such leather of the outer quarter or the leather of the soft sole. This problem is not present in the hard-soled shoe or slipper because the thick hard sole provides a basis for building the heel thereon and allows the

extended edge of the sole and the heel built thereon to be trimmed without damage to the outer quarter and allows the breast of the heel to be trimmed as the hard sole is not so readily affected by the trimming operation at the breast of the heel and is not damaged if the knife or other tool cuts into the hard sole slightly. By using a pre-formed heel and even a heel which has been finished to the last step the danger of cutting or damaging the soft leather of the outer quarter or the soft leather of the soft sole just forward of the breast of the heel is obviated.

Where a slipper is formed as in Fig. 2 with one of my pre-formed heels but without a counter or inner or outer quarter the method of attachment is shown in Fig. 9. The soft sole projects the desired distance back upon the cup-shaped surface of the heel and the stiff shank next above the soft sole extends substantially to the back of the heel and is fastened to the heel by the main nails 42 driven from within the slipper down into the finished heel as already described. The hair felt filling 44 and the insole or sock lining 43 are then placed in position and its edges securely glued or cemented in position with its lower face adjacent its outer edge fitting flat upon the level face 31 of the heel seat. For slippers of this type the face 31 will be formed a little wider than used in the slipper of Fig. 1 in order to be sure that a secure and neat joint is effected between the lining and the heel.

What I claim as new and desire to secure by Letters Patent is:—

1. As a new article of manufacture a slipper having a soft sole terminating near the breast of the heel, a shank of stiff material extending beyond the rear of the sole, and a pre-formed rigid heel secured to the shank.
2. A slipper having a soft sole terminating near the breast of the heel, a shank of stiff material extending substantially to the rear of the heel, a counter, and a pre-formed rigid heel.
3. A slipper having a soft sole terminating near the breast of the heel, a shank of stiff material extending substantially to the rear of the heel, and a rigid heel formed and finished before being applied to the slipper and fastened to the slipper by nails passing from within the slipper through the shank into the heel.

55 In witness whereof I have affixed my signature, this 12th day of May, 1928.

WILLIAM HUBBARD.
